UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO, CANADA.

MANIFOLDING SALES-BOOK.

1,182,969.

Specification of Letters Patent. Patented May 16, 1916.

Application filed January 24, 1912. Serial No. 673,066.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding sales books, and with regard to certain more specific features thereof, to triplicate sales books.

The object of the present invention is to provide a simple and easily manipulated sales book having a support divided into two parts with a flexible connection between them, a main pad of original and duplicate sheets, and a second pad, the two being mounted upon the different parts of the support and the arrangement being such that, by tilting one part of the support relative to another, one of the used sheets may be withdrawn from between the leaves of the main pad and dropped into place under it, so that when the support is brought back to alignment the sheet is filed.

In the accompanying drawing, wherein is shown one of various possible embodiments of this invention:—Figure 1 is a perspective view showing the device in operative position, certain parts being torn away for the sake of clearness; Fig. 2 is an end view of the book shown in Fig. 1; and Fig. 3 is a central transverse sectional view showing the manner in which the triplicate leaves may be filed.

Similar reference characters refer to similar parts throughout the different views of the drawing.

Referring now to the drawing in detail, 1 denotes a rear cover of a sales book holder having connected therewith at one side a front cover 2 by means of a flexible connection 3, whereby the book may be folded into compact form and conveniently carried. The cover 2 is provided with pockets 4 at the top and bottom, into which the edges of a record card or detached sheets may be placed.

The rear cover 1 is divided into two parts, the larger or main part being denoted by the numeral 1, while a smaller part 5 is connected therewith along one side edge by

means of a hinge or flexible connection 6. The cover is preferably made of sheet metal or other stiff material and covered with leather. In triplicate books the support for the original and duplicate pad and the support for the triplicate pad were, in general, heretofore made in two parts of substantially the same size as the pads which they held, and when in use had a normal superimposed position. Such a heavy and cumbersome construction resulted in high cost of manufacture, the reduction of which is one of the objects of this invention. This construction also prevents the pad of original leaves from swinging entirely around under the holder.

The member 5 has formed, preferably integrally therewith, an abutment 7 which is turned inwardly at the top 8. This abutment not only acts as a secure means for holding the pad 9, but also provides a more convenient tip-up means for swinging the pad 9 upwardly away from the cover 1, as shown in Fig. 3, than to use the part 5 alone.

The pad 9 preferably comprises a continuously folded sheet forming a plurality of sets of original and duplicate leaves 10 and 11, respectively. The leaves are perforated at each end 12 to permit them being separated from each other and also along their side edge 13, whereby they may be separated from the stub of the pad.

A double faced carbon sheet 15 is bound with the leaves of the pad and extends over substantially their entire surface. The pad 9 is provided with a binding strip 16, shown more clearly in Fig. 3, between which and the bottom leaf of the pad is inserted a retaining means 17 directly connected with the abutment 7, whereby the pad may be easily inserted or removed.

To the edge of the cover 1, adjacent the hinge 6, is secured a second abutment or flange 18 provided with holding means 19 for securing a pad of triplicate leaves 20 in a suitable manner.

A convenient method of operating a book of this character is substantially as follows: The pads, after being inserted in the holder 105 on the flat support formed by the parts 1 and 5, are positioned substantially as shown in Figs. 1 and 2, with the main portion of the pad 20 turned back over the cover 2, the bottom leaf being inserted over the car- 110

bon sheet 15, and both placed between the original and duplicate leaves 10 and 11. By writing upon the original leaf 10 the impression will be transmitted to the reverse side of the triplicate leaf 21 and the face of the duplicate leaf 11. After the transaction has been recorded the pad 9 is swung upward, as shown in Fig. 3, by pressing down with the thumb on the flange 7. The back 5 of the pad 9 acts as a lever about the hinge 6 as a fulcrum. The device is very simple to manipulate, as the book is usually held in the left hand with the thumb on the flange 7 and the little finger holding the leaves of the pad 20 in place. This action 10 permits the sheet 21 to be drawn out from between the original and duplicate leaves, whence it falls upon the cover 1, as shown by the position of the leaves 22, Fig. 3. A 15 complete bound set of transactions is in this manner kept on file for future reference. The original and duplicate set of leaves are then torn from the pad 9 and disposed of as desired. The next original leaf is turned 20 back and the carbon sheet placed over the duplicate leaf and the next triplicate leaf laid over the carbon sheet, after which the original leaf is swung to the position shown 25 in Fig. 1. The book is then ready for further transactions. If, however, the operator 30 is through for the day, the cover 2 with the pad 20 may be swung over on top of the pad 9.

It will thus be seen that this invention 35 provides a light and compact device, easily carried about in one's pocket, accomplishing, among others, all of the advantages and objects above set forth.

As many changes could be made in the 40 above construction and many apparently widely different embodiments of this invention could be made without departing from the scope thereof, it is intended that all matter contained in the above description or 45 shown in the accompanying drawing shall be interpreted as illustrative and not in a limiting sense.

Having described my invention, what I 50 claim as new and desire to secure by Letters Patent is:

1. In a manifolding sales book, a support, a pad of original and duplicate leaves secured to one edge of the support, the pad being formed from a continuously folded 55 web, the leaves of which are bound together along one side edge, a triplicate pad secured adjacent to another edge of the support, and a carbon sheet associated with one of the pads.
- 60 2. In a manifolding sales book, in combination, a support comprising a pair of parts and a flexible connection between them, a pad of continuously folded zigzag leaves se-

cured along an edge at right angles to its folds to one of said parts, said leaves extending when in operative position over the other of said parts, a second pad of leaves secured to the second part, a leaf of said second pad extending when in operative position over a leaf of the first pad and over the 65 second part, and a double-faced carbon sheet arranged when in operative position between leaves from each pad, to produce a plurality of records.

3. In a manifolding sales book, in combination, a support divided into two parts 75 flexibly connected so that one may be tipped relative to the other about the flexible connection, a main pad of original and duplicate leaves mounted upon one part of the support and moved therewith when it is tipped, a second pad mounted upon the other part of the support in position to coöperate with the first pad, and a double-faced carbon sheet connected to one of the pads; the 80 arrangement being such that a sheet of the second pad may be disposed upon the carbon sheet, and when the parts of the support are relatively tipped the sheet of the second pad will be withdrawn and disposed between the 85 main pad and the support.

4. In a manifolding sales book, in combination, a support divided into two parts, one of which is flexibly connected to the other and also to a cover, flanges on each part of 90 the support, a main pad of original and duplicate leaves carried by the flange upon one part of the support, a second pad of leaves carried by the flange upon the other part of the support, and a double-faced carbon sheet bound with the main pad; the 95 arrangement being such that a leaf of the second pad may be disposed upon the carbon sheet, and one part of the support may be tipped relative to the other to lift the main 100 pad and thus withdraw the said leaf and permit it to be disposed below the main pad.

5. In a manifolding sales book, a support 105 made in two parts, a flexible connection between them, a main pad formed from a continuous web folded zigzag and secured to one part of the support, a second pad of leaves secured to the other part of the support so that a leaf thereof may overlie the 110 first pad; and a double-faced carbon sheet 115 associated with one of the pads, the tipping of one part of the support relative to the other acting to withdraw the leaf of the second pad; as described.

In testimony whereof I affix my signature, in the presence of two witnesses.

EDWARD KIRBY BOTTLE.
